UNITED STATES PATENT OFFICE

2,152,715

RAILWAY CAR HAND BRAKE

Edwin E. Van Cleave, Chicago, Ill., assignor of
one-half to Alois Weidenbauer, Chicago, Ill.

Application July 21, 1937, Serial No. 154,810

7 Claims. (Cl. 188—153)

This invention relates to hand operated hydraulic means for operating the brake mechanism of railway cars.

The general purposes of the invention are similar to that of a disclosure in a co-pending application for patent by Edwin Van Cleave and Alois Weidenbauer on Hydraulic brake for railway cars, Serial No. 90,935, filed July 16, 1936, but an additional purpose of the present invention is the provision of automatic mechanical holding means serving to keep the brakes applied irrespective of any possible reduction in pressure in the hydraulic part of the mechanism.

Other features of the invention are a more direct leverage connection between the hydraulic plunger and the brake rigging, a more symmetrical and simple construction including changes rendering hydraulic brake operating means more particularly suitable for railway cars, and the use of a plurality of pressure creating plungers of differing capacities whereby a quick take-up may be followed by the use of a low capacity high-pressure plunger and cylinder.

A further object of the invention is to provide an automatic valve arrangement for cutting out the large capacity cylinder upon a predetermined motion of the brake-operating ram.

These objects are accomplished by means of a construction as illustrated wherein:

Fig. 1 is a fragmentary end view of a box car with the improved brake-operating means applied thereto.

Fig. 2 is a sectional view as indicated by the line 2—2 on Fig. 1.

Fig. 3 is an enlarged front view partly in section of a hydraulic brake-operating unit.

Fig. 4 is a transverse sectional detail of the operating unit.

Fig. 5 is a horizontal sectional view of the unit as indicated by the line 5—5 on Fig. 4.

Fig. 6 is a plan view of the operating unit.

Fig. 7 is a sectional detail of a cylinder cut-out valve mechanism moved to the cut-out position. The valve is shown closed in Fig. 4 and open in Fig. 7.

So far as known, the universal practice in hand-operated supplemental brake-operating means for railway cars is the employment of mechanical connections for insuring the application of the brakes independently of the air brake system. A hydraulic system for this purpose has the advantage of permitting the use of variable leverage in the hand-operated brake applying means and also provides for a graduated release without necessitating the operator's resisting the

reactive force from the released brakes. For successful practical use, hydraulic brake-operating means should comply in the matter of dimensions, location, form and simplicity and convenience of operation with established provisions for brake-operating mechanism. The illustrated construction is designed in its general lay-out and details with these provisions in view.

In the drawings there is shown one end 1 of a standard box freight car, having the customary ladder 2 and platform 3 for the brakeman. A fragment of the usual brake rigging connections including chain 4 and quadrant 5 are shown beneath the car. This quadrant or bell crank 5 is connected by a vertical link 6 with a vertically movable rod 7 by hinge connections 8. Rod 7 has a head 9 at its upper end resting upon a piston or ram 10 of cylindrical form. The hydraulic packing ring 11 is attached to the lower end of the ram and fits between the inner and outer cylindrical walls 12 and 13 of the ram cylinder 14.

This cylinder is shown as an integral part of a casting 15 which also forms a liquid supply reservoir 16 and operating plunger cylinders 17 and 18. Operating plungers 19 and 20 fit the cylinders 17 and 18 and their function is to lift the ram 14 by pumping fluid from the reservoir 16 through check valves 21 and 22, Fig. 5, into the lower end of cylinder 14 beneath the ram 10.

The plungers 19 and 20 are operated in unison by a hand lever 23 which is fulcrumed at 24. Fig. 3 to the lower end of a link 25 suspended from ears 26 projecting from casting 15. The purpose of the link 25 is to allow for strictly vertical motion of the plungers 19 and 20 which are attached by means of the pivots 27 to operating lever 23. The intake ports 28 and 29 for cylinders 17 and 18 are shown in Fig. 5 as controlled by the check valves 30 and 31.

The two cylinders 17 and 18 have sufficient pumping capacity for rapidly taking up the slack in the brake rigging and applying the brakes through a few oscillations of the lever 23, but when the ram 10 arrives at a position where great force is required for the final application of the brakes a small plunger 32, Fig. 4, is uncovered by the ram. This plunger is mounted in the wall of the cylinder 13 and extends into the reservoir 16. A pin 33 limits the movement of the plunger 32 under the action of a spring 34.

When the ram uncovers the plunger it is pressed in the direction of the reservoir against the action of the spring and rocks a lever 35 to which the plunger 32 is pivoted. The lever is fulcrumed at 36 and at its lower end carries a

slide valve 37. This valve is apertured at 38 for the purpose of opening a port 39 between pump cylinder 17 and reservoir 16.

When the port 39 is opened the liquid moved by plunger 19 by-passes back into the reservoir 16 and the entire load of further application of the brakes is taken by the low capacity plunger 20.

One side of the ram 10 is provided with ratchet teeth 40, and a pawl 41, by engagement with these teeth, serves to mechanically hold the brakes in applied position. This pawl is connected by a link 42 to a weighted arm 43. The pawl is thus held by gravity in engagement with the teeth, but may be disengaged for the purpose of releasing the brakes by a manual operation of arm 43. The pivot 44 for this arm affords a rigid bell crank connection between the arm 43 and the depending arm 45, the latter, through link 46, is connected with a crank arm 47 of a needle valve 48 controlling a bleeder or return flow port 49 between cylinder 14 and the reservoir 16 (Fig. 5). The needle valve has threaded engagement 50 with a boss in the wall of the supply reservoir. A lost motion connection 51 (Fig. 3) is provided between link 46 and the crank 47 to insure that the pawl 41 is disengaged prior to return flow of liquid from the cylinder 14 to the reservoir 16. In case of undue pressure between the teeth 40 and pawl 41 resisting motion of the operating arm 43, this may be relieved by the downward motion of operating lever 23.

In the operation of the hydraulic brake applying means the brakes are applied by a few oscillations of lever 23 and released by the opening of valve 48 through throwing the arm 43 backward, Fig. 3.

When the lever 23 is oscillated plungers 19 and 20 pump fluid from reservoir 16 to beneath the ram 10, lifting the ram, and through the rod 7 applying the brakes. When the ram moves far enough to uncover the by-pass valve operating plunger 32, port 39 is opened and allows for free circulation of liquid between the reservoir 16 and cylinder 17. Thus, from that point on the operation of plunger 19 is idle and plunger 20 takes the load. When the brakes are fully applied further action of operating lever 23 is manually impossible, and the set position of the brakes is held by pawl 41. Release of the brakes is effected by shifting the weighted bell crank arm 43 to the right (Fig. 3), which motion moves valve 48, Fig. 5, away from port 49 and allows the liquid in the ram cylinder to slowly return to reservoir 16, according to the reactive force of the brake mechanism in a downward direction on the headed rod 7. Whenever the port 49 is open, pawl 41 is disengaged and allows for free return motion of the ram.

The mounting of the brake operating unit has not been described, as it is identical to that employed for standard mechanical handbrake mechanism. The bolt holes in the supporting structure are in the same location.

There are numerous advantages to be had through use of a hydraulic brake-operating means of the character herein-described; for example, the plurality of operating plungers of different capacities in effect are of the nature of mechanical means having changing lever ratios whereby there is a quick take-up of slack in the rigging and the needed extended leverage for final forceful application of the brakes. The construction is easily operated and convenient for

full release or partial release of the brakes, or release of the brakes by any desired increments.

It is a long-lived structure, since the parts are few and rugged and the liquid may be of a lubricating nature. The particular arrangement of vertical operating rod coaxial with the surrounding ram and ram cylinder, provides for compactness, small dimensions and direct transmission of the thrust of the ram.

I claim:

1. In a hand brake operating mechanism for railway cars, a supporting frame structure arranged for attachment to a vertical end wall of a railway car and comprising a unit including a ram cylinder having inner and outer cylindrical walls, a ram plunger in the form of a cylinder fitting between the inner and outer walls of said ram cylinder, a brake operating rod extending vertically inside the inner wall of the ram cylinder and having an operative connection with the top of the ram plunger, and pump means for forcing fluid into the bottom of the ram cylinder, and means controlling said ram plunger to automatically change the effective capacity of said pump means for differential application of power to said ram plunger.

2. A brake operating construction arranged for mounting on a vertical end wall of a railway car and including a ram cylinder, a ram slidably mounted in said cylinder, a plurality of pump cylinders in communication with said ram cylinder, plungers fitting said pump cylinders, means for operating said plungers whereby liquid is forced from the pump cylinders into the ram cylinder, means for automatically rendering one of said pump cylinders and its plunger ineffective for forcing liquid into said ram cylinder after a predetermined motion of said ram in the cylinder, and another of said pump cylinders and its plunger being independent of said means.

3. In a hand operated hydraulic brake mechanism for railway cars, a frame structure having mounted thereon manually operated pump actuating means, a pump plunger operated by said means, a cylinder for said plunger, a ram cylinder, a ram movably supported therein, a supply reservoir for liquid; means affording a circuit of passageways between the supply reservoir, pump cylinder, ram cylinder and back to the supply reservoir; a ratchet-toothed rack on said ram, a pivoted pawl on said frame for retaining the ram in successive positions, a valve controlling the flow of fluid from said ram cylinder to the supply reservoir, and a weighted bell crank linked to said pawl to hold same engaged and disengaged with said rack and linked to said valve to hold same closed when the pawl is engaged and open when the pawl is disengaged.

4. A hand-operated brake mechanism arranged for mounting on the vertical end wall of a railway car, comprising a hydraulic ram, fluid pumping means for actuating said ram, a hand lever for operating said pumping means, said pumping means comprising a plurality of pump cylinders, a by-pass connection for rendering one of said pump cylinders ineffective, and means automatically controlling said by-pass connection through the position of said ram.

5. In a hand-operated hydraulic brake mechanism for railway cars, a frame structure having mounted thereon manually operated pump actuating means, a pump plunger operated by said means, a cylinder for said plunger, a ram cylinder, a ram movably supported therein, a supply reservoir for liquid; means affording a circuit of pas-

sageways between the supply reservoir, pump cylinder, ram cylinder and back to the supply reservoir; a ratchet-toothed rack on said ram, a pivoted pawl on said frame for retaining the ram in successive positions, a valve controlling the flow of fluid from said ram cylinder to the supply reservoir, and a weighted arm connected to said pawl to hold same engaged and disengaged with said rack and connected to said valve to hold same closed 10 when the pawl is engaged and open when the pawl is disengaged.

6. In a hand-operated hydraulic brake mechanism for railway cars, a frame structure having mounted thereon manually operated pump actuating means, a pump plunger operated by said means, a cylinder for said plunger, a ram cylinder, a ram movably supported therein, a supply reservoir for liquid; means affording a circuit of passageways between the supply reservoir, pump cylinder, ram cylinder and back to the supply reservoir; a ratchet-toothed rack on said ram, a pivoted pawl on said frame for retaining the ram in successive positions, a valve controlling the flow

of fluid from said ram cylinder to the supply reservoir, and a weighted arm having connection to move and hold said pawl engaged and disengaged with said rack and having connection to move and hold said valve closed when the pawl is engaged and open when the pawl is disengaged, there being lost motion in one of said connections whereby the disengaging movement of the pawl will precede the opening of said valve. 5

7. A brake operating construction arranged for mounting on a vertical end wall of a railway car and including a ram cylinder, a ram slidably mounted in said cylinder, a plurality of pump cylinders in communication with said ram cylinder, plungers fitting said pump cylinders, means for operating said plungers whereby liquid is forced from the pump cylinders into the ram cylinder, by-pass means for rendering one of said pump cylinders and its plunger ineffective for forcing liquid into said ram cylinder, and means actuated by pressure of the ram operating fluid for controlling said by-pass means. 10 15 20
